C. B. GILMORE

HOOD LATCH

Filed Jan. 24, 1925

Inventor
Charles B. Gilmore
by Parker + Carter, Attorneys.

UNITED STATES PATENT OFFICE.

CHARLES B. GILMORE, OF CHICAGO, ILLINOIS, ASSIGNOR TO CHICAGO FORGING & MANUFACTURING COMPANY, OF CHICAGO, ILLINOIS, A CORPORATION OF ILLINOIS.

HOOD LATCH.

Application filed January 24, 1925. Serial No. 4,368.

To all whom it may concern:

Be it known that I, CHARLES B. GILMORE, a citizen of the United States, residing at Chicago, in the county of Cook and State of Illinois, have invented a certain new and useful Improvement in Hood Latches, of which the following is a specification.

This invention relates to a fastening device, and particularly to a device intended 10 for use as an automobile hood latch. One object of the invention is to provide a device which will be used as a hood latch and which while serving to hold the hood down and closed will also force the hood in and 15 against other parts of the automobile, and thus hold the hood against rattling. Other objects will appear from time to time throughout the specification and claims.

My invention is illustrated more or less 20 diagrammatically in the accompanying drawings, wherein:

Figure 1 is a side elevation of one form 25 of the latch showing it in position on the automobile;

Figure 2 is a vertical cross section taken on line 2—2 of Figure 1;

Figure 3 is a view similar to Figure 1 showing a modified form with parts in section;

30 Figure 4 is an elevation of the form shown in Figure 3 with parts in section.

Like parts are designated by like characters throughout.

A is a portion of an automobile frame. To 35 it is fastened an upstanding rib or holding part A¹ against which a part of the hood cover B rests when the hood is closed. Fastened to the hood cover is an inclined locking member B¹. It is preferably mounted 40 so that it may be moved laterally for adjustment. The locking member is provided with an inclined portion B² having up-standing edges or lips B³.

C is a shaft squared as at C¹ and rounded 45 as at C² and provided with a reduced portion C³. It is mounted upon the member A in a fitting D¹ and provided with an engaging part D² adapted to be forced into contact with a narrowed portion C³ of the shaft C. The shaft is provided with an enlarged washer or other lateral projecting 50 member C⁴ adjacent its upper end.

Surrounding the shaft is an enclosing and

spring retaining member E. At its lower end it is provided with a square opening E¹ 55 through which the shaft C passes. The parts are thus squared to prevent turning of the member E upon the shaft C.

Within the member E and bearing at one end upon its lower end and at the other 60 upon the washer C⁴ is a helical spring F. The spring tends normally to hold the parts in the position shown in Figures 1 and 2 to resist upward movement of the member E.

The member E has an open side facing the 65 hood. Mounted across and above this side is a latch member G. It is provided at its lower end with a laterally bent portion G¹ having a square opening G² in it and through this opening the shaft C passes. At its upper end the member G is laterally and downwardly bent as at G³ to provide a handle. Intermediate its ends it is provided with an inclined cam portion G⁴ which when the 70 parts are in the locking position bears with 75 a cam action upon the inclined face B² of the member B¹ and holds the hood portion closed, and also with the cam action forces it inward to prevent rattling movement of the 80 parts.

In the modified form shown in Figures 3 and 4 a square shaft H is mounted for swinging movement on a pin H¹ carried in a bearing supporting member H². At its upper end the shaft H is provided with a 85 laterally enlarged washer H³. The shaft H is provided with a rounded portion H⁴ above the squared portion at the lower end. Surrounding the shaft H is a generally cylindrical handle member I. It is provided 90 with laterally extended handle portions I¹ I¹ and is closed at its bottom by a closing member I² which is provided with a square opening through which the shaft H passes. Surrounding the shaft H within the housing 95 member I, bearing at one end upon the member I² and at the other upon the member H² is a helical spring I³ which tends to hold the parts in the position shown and resist upward movement of the handle member. 100

Extending laterally from the member I is a hook portion J. This hook portion is provided as shown with a similar inclined cam surface J¹ J¹.

K is an inclined handle member mounted 105 on the hood B. When the hood is closed,

one of the cam surfaces J^1 of the hook J bears with a cam action upon the handle member K and holds the parts locked and also forces the hood member B inward to prevent rattling.

Although I have shown an operative device, still it will be obvious that many changes might be made in size, shape and arrangement of parts without departing materially from the spirit of my invention; and I wish, therefore, that my showing be taken as in a sense diagrammatic.

The use and operation of my invention are as follows:

15 When the hood is to be opened, the handle is raised. The locking cam portion of the member G is moved out of engagement with the member B^2 and the hook may be swung downward to the side out of the way. The 20 hood may then be opened. When the device is again to be locked the hood is closed, the handle portion is raised, pulled upward and the locking member is brought into engagement again with the member B^2 , and in this 25 position because of the inclined contacting faces of the two parts B^2 G^4 the hood is held closed and is also forced inward. Thus when wear of the parts takes place under the 30 action of the spring, the parts will be forced constantly together, and even though as a result of wear the hood portion B may move farther in, the pressure of the spring will force the locking member G^4 farther down and the hood will always be forced inward 35 so far as there is any contact of the parts G^4 upon the part B^2 .

In the form shown in Figures 3 and 4 the locking action is the same as that above described, the cam face J^1 being forced by 40 the spring against the handle member K . The shaft is square and an enclosing member is provided with a square perforation so that relative rotation of the two is normally impossible. It is desirable, however, to 45 permit this rotation for certain purposes, particularly when it is desired to have the hook member brought on the opposite side of the enclosing cylindrical member. For this purpose a portion of the shaft is rounded. In normal operation the square closing 50 member is not drawn up far enough to reach the rounded portion. When, however, it is desired to rotate the handle member about the shaft, it is drawn up farther than is 55 usual in opposition to the spring, and then the square closing portion I^2 moves upon the rounded portion of the shaft H^4 and rotation of the two is possible. Then the handle member may be rotated throughout 60 180° and the parts moved down so that the closing member is again upon the square portion of the shaft, and in this association relative rotation of the parts is impossible.

By this construction a closing latch is 65 made which can be adjusted to be used on

either side of a fixed handle, and it is unnecessary to make rights and lefts, and one latch is made and it may be used either as a right or left by adjustment as above described.

70

I claim:

1. In combination with a closure and a latch support, a latch for said closure mounted upon said support, and adapted to be moved laterally past said closure and held 75 against movement away from said closure, said latch including a hook member provided with an inclined cam face, and a hook receiving member on said closure, said cam face adapted to be seated upon said receiving member to hold the closure closed and to force the same inward.

2. In combination with a closure and a latch support, a latch for said closure pivotally mounted upon said support, and adapted to be swung laterally past said closure and held against movement away from said closure, said latch including a hook member provided with an inclined cam face, and a hook receiving member on said closure, 80 said cam face adapted to be seated upon said receiving member to hold the closure closed and to force the same inward.

85

3. In combination with a closure and a latch support, a latch pivotally mounted on said support and adapted to be moved along said closure and held against movement away from said closure, said latch including a movable latch member normally spring held in engaging position, said member provided with an inclined cam face, and a latch engaging member on said closure, said inclined face adapted to engage and to be seated upon said latch engaging member to hold the closure down and to force the same inward.

95

4. In combination with a closure and a latch support, means for holding the closure closed and for forcing the same progressively inward, said means including a latch member pivotally mounted on said support for movement past said closure and held against movement away from said closure, and an engaging member on said closure, said latch including a movable, inclined cam member adapted to be received by said seating member and thereby to hold the closure down and to force the same inward.

105

5. In combination with an automobile, a hood, a latch member mounted adjacent said hood, and adapted to rotate about an axis generally at right angles to said hood, and held against swinging movement outward from said hood, said latch member provided with an inclined cam engaging member and having a spring adapted normally to hold said member down, there being mounted upon said hood a cam receiving member adapted to be engaged by said cam member whereby the hood is held closed and forced 115

120

125

130

inward by the cam action of said two members one upon the other.

6. In combination with a closure and a latch support, a latch for said closure mounted upon said support, and adapted to be swung along said closure and held against movement away from said closure, said latch including a pivoted shaft member and a hollow casing enclosing the same, a hook member supported from said shaft, a spring in said casing adapted to resist outward movement of said hook member, said hook member provided with an inclined cam face, and a hook receiving member on said closure, said cam adapted to be seated upon said receiving member to hold the closure closed and to force the same inward.

7. In combination with a closure and a latch support, a latch for said closure mounted upon said support and adapted to be moved laterally past said closure and held against movement away from said closure, the latch including a shaft having a squared portion and a cylindrical housing mounted upon said shaft, a spring about said shaft within said housing adapted to resist outward movement of the housing along the shaft, said housing provided with an inclined hook member and a hook receiving member on said closure, said hook adapted to be seated upon said receiving member to hold the closure closed.

8. In combination with a closure and a latch support, a latch for said closure mounted upon said support and adapted to be moved laterally past said closure and held against movement away from said closure, the latch including a shaft having a squared portion and a cylindrical housing mounted upon said shaft, a spring about said shaft within said housing adapted to resist outward movement of the housing along the shaft, said housing provided with an inclined cam hook member and a hook receiving member on said closure, said hook adapted to be seated upon said receiving member to hold the closure closed, said housing provided with a closure having a square opening embracing the square shaft, the shaft provided with a rounded portion whereby when the housing is raised above

its normal travel it may be rotated about the shaft to bring the hook on the opposite side.

9. In combination with a closure and a latch support, a latch for said closure mounted upon said support, and adapted to be moved laterally past said closure and held against movement away from said closure, said latch including an engaging part provided with an inclined cam face, and a receiving member on said closure, said engaging part adapted to be seated upon said receiving member to hold the closure closed.

10. In combination with a closure and a latch support, a latch for said closure pivotally mounted upon said support, and adapted to be swung laterally past said closure and held against movement away from said closure, said latch including an engaging member provided with an inclined cam face, and a receiving member on said closure, said engaging member adapted to be seated upon said receiving member to hold the closure closed.

11. In a hood latch the combination with a closure, of a latch support pivoted adjacent thereto on an axis at right angles to the face of the closure, a latch element slidable along said support, yielding means normally tending to thrust said latch downwardly along said support and a cam connection between said latch and said support adapted to exert pressure downwardly and inwardly against the lower edge of the closure.

12. In a hood latch the combination with a closure, of a latch support pivoted adjacent thereto on an axis at right angles to the face of the closure, a latch element slidable along said support, yielding means normally tending to thrust said latch downwardly along said support, a downwardly and outwardly inclined cam member mounted on said closure and an opposed upwardly and inwardly inclined cam member mounted upon said latch and adapted to seat upon said first mentioned cam.

Signed at Chicago, county of Cook and State of Illinois, this 19th day of January 1925.

CHARLES B. GILMORE.
